UNITED STATES PATENT OFFICE

ARTHUR W. FISHER, OF FOREST HILLS, PENNSYLVANIA

DESIGN FOR A HIGHWAY-CROSSING SIGNAL

Application filed October 6, 1930. Serial No. 37,157. Term of patent 14 years.

To all whom it may concern:

Be it known that I, ARTHUR W. FISHER, a citizen of the United States, residing at Forest Hills, in the county of Allegheny and State of Pennsylvania, have invented a new, original, and ornamental Design for Highway-Crossing Signals, of which the following is a specification, reference being had to the accompanying drawing, forming part thereof.

Fig. 1 is a front plan view of a highway crossing signal, showing my new design, and, Fig. 2 is a side view of said signal.

I claim:

The ornamental design for a highway crossing signal, as shown.

ARTHUR W. FISHER.
